United States Patent Office

Des. 189,786
Patented Feb. 21, 1961

189,786

KITCHEN UNIT

Robert L. Irwin, 315 Holland-Sylvania Road, and Earl J.
Duvall, 1628 Glenton Drive, both of Toledo, Ohio

Filed Aug. 3, 1959, Ser. No. 57,039

Term of patent 7 years

(Cl. D33—19)

FIG. 1

FIG. 2

Fig. 1 is a front view in perspective of a kitchen unit showing our design; and

Fig. 2 is a rear perspective view thereof.

The dominant features of our design reside in those portions shown in full lines in the drawings.

We claim:

The ornamental design for a kitchen unit, substantially as shown and described.
